WILLIAM HAILES, OF ALBANY, NEW YORK.

Design No. 2,913, dated February 4, 1868.

DESIGN FOR A STOVE.

The Schedule referred to in these Letters Patent and making part of the same.

Be it known that I, WILLIAM HAILES, of the city of Albany, State of New York, have produced a new and original ornamental Design for a Hall-Stove, (stove being named the Brilliant;) and I declare the annexed drawings, exhibiting in perspective the stove, to be a full and accurate delineation of its plates with their ornaments; the parts of the stove not shown being symmetrically similar to the parts shown.

What I claim, and desire to secure by Letters Patent, is—
The design for a hall-stove, as shown and described.
